United States Patent Office

Des. 181,681
Patented Dec. 10, 1957

181,681

ALTAR OR SIMILAR ARTICLE

Arloe L. Shelton, Odessa, Mo.

Application May 13, 1957, Serial No. 46,125

Term of patent 14 years

(Cl. D29—23)

Fig. 1.

Fig. 2.

Fig. 3.

Fig. 1 is a front perspective view of an altar or similar article, showing my new design;

Fig. 2 is a side elevational view thereof; and

Fig. 3 is a top plan view of the altar or similar article. The back of the design is without ornamentation.

I claim:

The ornamental design for an altar or similar article, as shown and described.
